FIG.-1

FIG.-2

FIG.4

FIG.3

FIGURE 1 is a top plan view of an electromagnetic radiation apparatus showing our new design;

FIGURE 2 is a front elevational view thereof;

FIGURE 3 is an isometric view thereof; and

FIGURE 4 is a left side elevational view with a portion thereof broken away.

The rear of the apparatus not shown is substantially a mirror of the front as shown in FIGURE 2.

The essential features of our design reside in the portions shown in full lines.

We claim:

The ornamental design for an electromagnetic radiation apparatus, as shown and described.
